Filed Oct. 1, 1963, Ser. No. 313,026

5 Claims. (Cl. 273—95)

This invention relates to a novel toy satellite system. The primary object of the invention is the provision of a highly realistic, amusing, and educative system of the kind indicated, which includes a simulated launching pad having a spring-operated launcher, a moon ship or multi-stage rocket having a first-stage, adapted to be launched by the launcher to and to be held magnetically by a space stratum, from which a simulated second-stage is spring-launched, by the first-stage, to a moon, to which the second-stage is held magnetically, the second-stage having spring-operated launching means for a satellite carried thereby, whereby the satellite is launched into an orbit around a planet, the planet having a rotating magnet assembly which draws the satellite to the planet and moves the same around the planet.

Another object of the invention is the provision, in a planet of the character indicated above, of a planet which contains an electrically driven magnet assembly which is energized by a solar battery, which is operable either by sunlight or electric light.

Other important objects and advantageous features of the invention will be apparent from the following description and the accompanying drawings, wherein, for purposes of illustration only, a specific form of the invention is set forth in detail.

FIGURE 1 is a schematic perspective view of a satellite system of the present invention, showing a multi-stage rocket in transit between the launching pad and a space station, a second multi-stage held by the space section, a second-stage of the latter being shown in transit to a moon, another second stage magnetically held to the moon, and a satellite in transit between the second stage in transit to the planet, and another satellite in orbit around the planet;

FIGURE 2 is an enlarged vertical transverse section taken on the line 2—2 of FIGURE 1, showing the multi-stage rocket in place in the launcher, with its trigger spring retained in inoperative position, and the launching spring retained in compressed condition;

FIGURE 3 is a fragmentary view, like FIGURE 2, showing the multi-stage rocket emerging from the launcher, with its trigger spring released and its tilting magnet repelled by the tilting magnet of the launcher, for tilting the rocket, as shown in phantom lines, into a trajectory to reach the space station;

FIGURE 4 is a horizontal section taken on the line 4—4 of FIGURE 2;

FIGURE 5 is a vertical longitudinal section taken on the line 5—5 of FIGURE 1, and a multi-stage rocket secured magnetically thereto, and a second stage being propelled therefrom;

FIGURE 6 is a vertical transverse section taken on the line 6—6 of FIGURE 5;

FIGURE 7 is a side elevation, partly broken away and in section, of the moon, showing the magnet holding a second-stage to the moon;

FIGURE 8 is a vertical longitudinal section showing the said second-stage launching the satellite;

FIGURE 9 is a vertical transverse section taken on the line 9—9 of FIGURE 8;

FIGURE 10 is an enlarged vertical transverse section taken on the line 10—10 of FIGURE 1, showing a satellite adhered thereto and in orbit therearound;

FIGURE 11 is a horizontal section taken on the line 11—11 of FIGURE 10; and

2

FIGURE 12 is a transverse section taken on the line 12—12 of FIGURE 11.

Referring in detail to the drawings, the illustrated satellite system comprises a launching pad LP, one or more multi-stage rockets or moonships R, a space station ST, a moon M, and a planet P, suitably supported above and down-line from the launching pad.

The launching pad LP comprises a frusto-pyramidal stand 12 having a rectangular base plate 14, from whose corners fixed upwardly convergent legs 16 extend to and are fixed to the corners of a rectangular platform 18, the last being smaller in area than and centered relative to the base plate 14. A perpendicular first-stage launching tube 20 is fixed, at its lower end, to the center of the base plate 14 and extends upwardly through a centered opening 22, provided in the platform 18, to a substantial height above the platform.

As shown in FIGURES 2 through 4, the launching tube 20 is open, at its upper end, which has an upper edge which has, on its side thereof facing the space between S, an upstanding leg 24, on which is fixed a vertical flat permanent magnet 28.

At a level spaced below the platform 18 and above the base plate 14, the launching tube 20 has an internal partition 30, formed with a central opening 32, through which a cylindrical plunger rod 34 works. The rod 34 has a fixed, enlarged diameter collar 36, on its lower end, which slides within the tube 20, bears upon the upper end of a coil propulsion spring 38, whose lower end rests upon the base plate 14, around an air-vent opening in the base plate. An annular resilient and compressible pad 40 is circumscribed on the rod 34 and is secured on the upper surface of the collar 36, the pad being adapted to engage the partition 30, as the spring 38 drives the rod 34 upwardly, and absorb the resultant shock and noise. The rod 34 has an enlarged diameter head 42, on its upper end, above the partition 30, which is somewhat smaller in diameter than the bore of the launching tube, and which is adapted to engage and support the lower end of a multi-stage rocket assembly R, within the upper part of the launching tube, preliminary to launching of the assembly, as shown in FIGURE 2. The plunger rod 34 is adapted to be manually depressed to cocked position, wherein the spring 38 is compressed, by inserting a rocket assembly R in the upper end of the tube 20 and forcing the same downwardly until the pad 40 is on a level below a radial bore 43, in the side wall of the tube 20. The bore 43 is provided to receive a removable stop pin 45, adapted to engage the top of the pad 40 and hold the rod 34 down in cocked position. The pin 45 has a ring 47, on its outer end, to which a releasing cord 49 is secured, which is adapted to be pulled to retract the pin 45 and release the plunger rod for propelling the rocket assembly R out of the launching tube.

The multi-stage rocket R comprises a longitudinally elongated hollow cylindrical casing 44, having a uniform diameter side wall 46, and a rear end wall 48, provided with a centered air-vent opening 50. The side wall 46 is formed with a pair of diametrically opposed, longitudinal fins 52, which, as shown in FIGURE 4, are positioned in longitudinal guide slots 54, provided in the side wall of the launching tube 20, for properly positioning the rocket R therein.

A second stage launching spring 56 is positioned in the casing 44, with its lower end suitably secured to the end wall 48, and with its upper end suitably secured around a reduced diameter boss 58, on the lower end of a cylindrical plunger 60. The lower part of the plunger 60 is smaller in diameter than and centered in the casing 44, and has an enlarged diameter upper portion 62, which bears slidably against the side wall 46 of the casing 44.

An annular detent groove 64 encircles the plunger below the upper portion 62.

The detent groove 64 is provided to receive an intermediate detent lug 66 on a longitudinally elongated trigger leaf spring 68, working through a slot 70, in the casing side wall 46. The spring 68 has its upper portion suitably fixed to the exterior of the side wall 46, as indicated at 72, and the lower portion of the spring is outwardly biased, away from the casing 44. An outwardly directed detent lug 74, on the lower end of the spring 68, is engaged in a slot 76, in the bottom wall of a housing 82.

A downwardly tapering wedge 78 is fixed to the outer surface of the upper part of the spring 68, and is part of a time-delay assembly 80, which comprises a longitudinally elongated, relatively small cross section rectangular hollow housing 82, which is affixed to the side wall 46, and encloses the spring 68. The bottom wall 84 of the housing 82 is formed with a second wedge 86 opposed to and reversed with respect to the wedge 78. An elongated flexible and resilient capsule 88 extends along and is fixed to the inner side of the wedge 86. The capsule is closed and contains a body of fluid, such as oil, whose volume is less than the volumatic capacity of the capsule. The capsule is provided, midway between its ends, with a partition wall 92 which is formed with a bleeder opening 95.

In the launch position, shown in FIGURE 2, the capsule is under minimal compression, and its fluid lies in the lower portion thereof, so that the spring 68 is maintained in its inoperative position, against the casing side wall 46. When the socket R is launched, the wedge 78, in moving upwardly past the wedge 86, squeezes the lower part of the capsule so that the fluid 90 is forced up into the upper part of the capsule, through the bleeder hole 94, so that the trigger spring 68 is freed to swing outwardly, and release the plunger 60, to drive out of the casing 44, a second-stage 96.

The bottom wall of the housing 82 has an opening 98, at its lower end, which exposes a flat permanent magnet 100 of opposite polarity to the launching tube magnet 28, so that as these magnets pass each other, on launch of the rocket R, they repel each other and tilt the rocket R, as indicated in FIGURE 3, into trajectory to reach the space station ST.

The plunger 60 is formed, in its top, with a circular socket 102, in which is adapted to seat the open rear end of a relatively small diameter launching tube 104, of the second-stage 96. The launching tube 104 is surrounded by a body 106 of non-metallic resilient material, such as rubber or plastic material, which has a full diameter forward portion 108, which has a sliding fit in the casing 44 and a rearwardly tapered rear portion 110. A disc 112 of the diameter of the casing 44, is affixed to and closes the forward end of the tube 104, and carries, on its exposed surface, a flat disc magnet 114.

An elongated hollow rectangular housing 116, shorter than the launching tube 104 is affixed thereto, and has a closed forward end 118 and an open rear end 120. A compressible resilient time-delay capsule 122, similar to the capsule 88, is affixed to the bottom wall 124 of the housing 116, and biases against an elongated flat trigger leaf spring 126, which is fixed, at its forward end, to the casing side wall 46, and is outwardly biased therefrom. The spring 126 extends rearwardly out of the housing 116, and has, on its rear end, an outwardly directed detent lug 128, which bears against the casing side wall 46, and an intermediate inwardly extending detent lug 130, which in the inoperative position of the spring 126, engages through a slot 132, provided in the side wall of the tube 104, and engages retainably in a notch 134, intermediate the ends of an elongated plunger rod 136, which works in the launching tube 104. The plunger rod 136 is shorter than the tube 104 and has a reduced diameter boss 138, on its forward end, around which is secured the adjacent end of a coil spring 140, whose other end is suitably secured to the disc 112. The rod 136 is

provided, on its rear end, with a pair of opposed arcuate spring fingers 142, which releasably retain a magnetizable spherical satellite S, which, in the unlaunched condition of the second stage 96, the satellite is protectively contained with the launching tube 104, as shown in FIGURE 2, in which retraction, the spring 140 is compressed, and the intermediate trigger spring lug 130 is engaged in the notch 134 of the rod 136.

As the rocket R reaches and magnetically adheres to the space station S, the lower part of its capsule having been squeezed between the wedges 78 and 86, the spring 68 is permitted to move away from the casing 44, so that the plunger 60 is released to drive the second stage 96 toward the top of the moon M. As the second stage emerges from the rocket R, the same thing happens to the capsule 122 of the second stage 96, so that the trigger spring 126 thereof starts to move away from the launching tube 104.

The moon M comprises a solid spherical non-metallic body 144, suspended from a cord 146, or the like, and having embedded therein, an elongated bar magnet 148, which is disposed in an upward angle toward the planet P, and has an end 150 exposed flush with the surface of the body 144. As the second stage 96 reaches the top of the moon M, it tumbles forwardly thereover, as indicated in FIGURE 7, and, on reaching the vicinity of the magnet end 150, the disc magnet 114 of the second stage 96 is attracted to and becomes magnetically adhered to the magnet end 150, with its launching tube 104 directed, at an upward angle toward the planet P.

As the trigger spring 126 of the second stage 96 moves farther away from the launching tube 104, its intermediate lug 130 is withdrawn from the notch 134 in the plunger rod 136, so that plunger rod is driven part way out of the tube, and, on being arrested, the satellite S is released from between the spring fingers 142, and travels to the planet P.

As shown in FIGURE 12, the satellite S comprises a spherical magnet core 152 surrounded by a thick cover 154 of resilient and compressible material, such as rubber or plastic material, so as to avoid damaging contact of the satellite with the planet P.

As shown in FIGURES 10 and 11, the planet P is spherical and comprises an outer plastic material shell 156 and a concentric inner plastic material shell 158, which are spaced and connected by radial ribs 160. Both of these shells can be transparent.

Relatively small magnets 174 are secured to the inner surface of the inner shell 158, which serve to retract and draw toward the planet P, a satellite 158 nearing the planet, and to assist in its being carried around the planet by a magnetic rotor 176.

The magnetic rotor 176 is disposed within the inner shell 158 on a horizontal diameter of the planet, and comprises an elongated flat bar 178 having heavy thick magnet blocks 180 fixed thereon at the ends of the bar and positioned close to the inner shell 158. The bar 178 is fixed, at its center, on a cup 182, which receives an upstanding perpendicular shaft 184, to which it is pinned, as indicated at 186. The shaft 184 is supportably journaled through the upper member 188 of a gear frame 190, which, at its lower end, is fixed to a base frame 192 which is fixed, at its lower end, to the inner shell 158. An electric motor 194 is mounted upon the cross member 196 of the base frame 192 and has an upstanding shaft 198, which is operatively connected to speed reducing gearing 200, supported within the gear frame 190 and operatively connected to the rotor shaft 184, thereby the rotor 176 is rotated at a relatively slow speed. An outwardly facing solar battery 202 is fixed between the shells and connected to the motor.

The planet P is suspended, as from a ceiling (not shown) or the like, by means of a wire or cord 206, which is secured, as indicated at 208, to the inner shell 158, at the top thereof, and passes up through a hole 210 in the

outer shell 156, the arrangement being such that the planet remains still while the rotor 176 rotates.

The space station ST comprises a preferably solid elongated rectangular block 212, having conical ends 214, and formed, in its underside with a longitudinal groove 216, in which is secured an elongated flat magnet 218, whose outer underside is flush with the underside of the block 212. An upstanding eye 220 is secured in the top of the block 212, at a point forwardly of the middle of the block, so that the space station assumes an upwardly and forwardly tilted position, when suspended by a cord or wire 222, connected to the eye 220, from a support such as a ceiling (not shown). The magnet 218 serves to attract a multi-stage rocket assembly R reaching the immediate vicinity of the space station ST to the space station and hold the same in contact therewith, by means of the attraction of the magnet 218 for an elongated flat magnet 219 which is secured along the top of the casing 44 of the rocket assembly R.

The fact that the space station magnet 218 has north and south poles serves to position the space station with its north pole pointing toward the terrestrial north pole. Because of this position of the space station, the launching pad LP and the planet P must be lined up with the space station ST. Further, the space station ST must be positioned at the right height, relative to the trajectory of a rocket assembly R propelled from the launching pad LP, so that the assembly R will reach the space station on a line below and close to its underside and the magnet 218 of the space station. The planet P must be suspended at such a height that a satellite propelled toward the satellite would arrive thereat ideally in the plane of the equator and at either side of the planet.

It will be understood that the invention herein disclosed, is not limited to the use of only one moon, and that all of the components can be used in multiple.

While there has been shown and described a preferred form of the invention, it is to be understood that the invention is not necessarily confined thereto, and that any change or changes in the structure of and in the relative arrangements of components thereof are contemplated as being within the scope of the invention as defined by the claims appended hereto.

What is claimed is:

1. A satellite system comprising a launch pad, a space station spaced above and down-line from the launch pad, said station having a magnet on its underside, a moon in line with and spaced down-line from the space station and having a magnet on the side thereof remote from the station, a planet in line with and spaced down-line from the moon, said planet having rotating magnet means therein, a multi-stage rocket having a magnet on its upper side to be attracted to and held by the space station magnet when launched from the launching pad, said rocket having a second stage and means for launching the second stage toward the moon as the rocket reaches and is secured to the space station, said second stage having a magnet to be attracted to and held by the magnet of the moon, said second stage having a releasable magnetizable satellite, and means for launching the satellite toward the planet as the second stage is secured to the moon, the satellite being adapted to be attracted and moved around the planet by its rotating magnet means.

2. A satellite system according to claim 1, wherein said launching pad comprises a vertical launching tube containing an upwardly spring-pressed plunger rod, and means for releasably holding the plunger rod in depressed cocked position, said rocket being releasably engaged in the launching tube and resting upon said plunger rod, said rocket comprising a vertical tube smaller in diameter than the launching tube and having a vented bottom wall resting

upon the plunger rod, an upwardly spring-pressed plunger sliding in the rocket tube, a trigger leaf spring fixed at its upper end to the side wall of the rocket tube and having a lower portion biased away from this side wall, said spring having an inwardly extending intermediate detent lug, the side wall having an opening passing the lug and the plunger having an annular groove receiving the lug in the compressed condition of the plunger, a longitudinal hollow housing fixed on the side of the rocket tube opposite the magnet, said housing having a bottom wall formed with an opening, said spring having an outwardly extending lower detent lug at its lower end engaged through the bottom wall opening and bearing against the side wall of the launching tube, oppositely disposed and facing wedges on the housing bottom wall and the side wall of the rocket tube, a resilient and compressible time-delay capsule secured to one of the wedges and engaged with the other, said capsule containing liquid and having a partition wall intermediate its end provided with a bleeder opening, and said second-stage engaged in the rocket tube and resting upon the plunger.

3. A satellite system according to claim 2, wherein the plunger has a centered socket in its upper end, said second-stage comprising a launching tube smaller in diameter than the rocket tube and having an open lower end engaged in said socket, said magnet on said second stage being a disc magnet closing the upper end of the second-stage tube, the second-stage tube being surrounded by a cylindrical body of compressible and resilient material sliding in the rocket tube, a downwardly spring pressed plunger rod in the second-stage tube having a notch in one side thereof, a hollow housing fixed to and extending along one side of the second-stage tube and having an open lower end, said second-stage housing having a bottom wall, a trigger leaf spring fixed at its upper end to said bottom wall of said second stage housing and having a lower portion biased away from the side wall of said second stage housing, the side wall of the second-stage tube being provided with an opening, the second-stage trigger spring having an inwardly extending intermediate lug extending through said opening in said second stage tube and engaging in the notch of the second stage plunger rod in the retracted cocked position of said second stage plunger rod, and a second time-delay capsule similar to the first-mentioned time delay capsule secured along the bottom wall of the second-stage housing and engaging the outer side of the second-stage trigger spring, said plunger rod in said second stage having opposed spring fingers on its lower end, said satellite comprising a magnetizable sphere releasably engaged between the fingers.

4. A satellite system according to claim 3, wherein said second-stage trigger spring has an outwardly extending lug on its lower end adapted to engage the side wall of the rocket tube to hold the second-stage spring inwardly with its intermediate lug in retaining engagement with the plunger.

5. A satellite system according to claim 3, wherein said satellite comprises a magnetizable core and a non-metallic resilient and compressible cover.
